UNITED STATES PATENT OFFICE.

FRANK T. VANATTA, OF MILL VALLEY, CALIFORNIA, ASSIGNOR TO THE UNION SWITCH & SIGNAL COMPANY, OF SWISSVALE, PENNSYLVANIA, A CORPORATION OF PENNSYLVANIA.

SIGNAL.

REISSUED

Patented Feb. 12, 1918.

Specification of Letters Patent.

Application filed March 15, 1916. Serial No. 84,332.

To all whom it may concern:

Be it known that I, FRANK T. VANATTA, a citizen of the United States, residing at Mill Valley, in the county of Marin and 5 State of California, have invented certain new and useful Improvements in Signals, of which the following is a specification.

My invention relates to signals, and particularly to signals for use at grade crossings of railways and highways for the purpose of warning pedestrians and occupants of vehicles traveling on the highway of the approach of trains.

One object of my invention is the provision of a signal of this character which comprises a warning member, such as a semaphore, biased to occupy one position, which semaphore is held in another position when no train is approaching and the signal and controlling apparatus are in proper working condition, and which semaphore is caused to oscillate or "wag" to give a warning indication upon the approach of a train. The signal will therefore give one warning 25 indication when a train is approaching and all parts are in proper operative condition, and another and distinctive warning indication when any part of the signal or its controlling apparatus is out of order regardless of whether or not a train is approaching.

I will describe one form of signal embodying my invention, and will then point out the novel features thereof in claims.

In the accompanying drawings, Figure 1 35 is a view showing in front elevation one form of signal embodying my invention. Fig. 2 is an end view of the devices which are mounted on the free end of the arm 3 in Fig. 1. Fig. 3 is a fragmental view showing the range of movement of the warning member itself while the said member is giving the warning indication due to the approach of a train. Fig. 4 is a view partly in elevation, partly in section and partly diagrammatic, showing the mechanism M and also one form and arrangement of controlling apparatus and circuits for the signal. Fig. 5 is a sectional view on the line V—V 45 of Fig. 4 looking in the direction of the arrows. Fig. 6 is a sectional view on the line VI—VI of Fig. 4 looking in the direction of the arrows. Fig. 7 is a sectional view on the line VII—VII of Fig. 4, looking in the direction of the arrows.

50 Similar reference characters refer to similar parts in each of the several views.

Referring first to Fig. 1, the signal in the form here shown comprises a post or mast 1 mounted on a base or foundation 2 located at the side of the highway near the crossing of the highway and the railway. This post or mast 1 carries an arm 3 which projects across the highway so that the warning devices mounted on this arm near its outer end are located over substantially the middle of the highway where they can be plainly seen by pedestrians or occupants of vehicles using the highway.

Attached to the arm 3 near its outer end is a depending forked bracket 4 (see Figs. 70 1 and 2), the two arms of the fork constituting bearings in which a shaft 5 is mounted to oscillate. This shaft carries a pendulum-like device comprising a semaphore 7 and radial rods 6 which are rigidly attached to the shaft 5. The semaphore 7 constitutes the warning device of the signal, that is, the device which by its position or movement indicates to a traveler on the highway whether or not it is safe to cross the railway track. 80 This semaphore is referred to more broadly hereinafter in the claims as a "member mounted to oscillate". The semaphore 7 preferably has a warning legend, such as the word "Stop", inscribed thereon as indicated in Fig. 1, such legend generally appearing on both sides of the semaphore, and the semaphore also preferably carries one or more electric lamps 8 for giving a warning at night.

90 The semaphore 7 is controlled by a flexible connector 9, preferably a wire, one end of which terminates in a short length of chain 9^a which passes over and is attached to a grooved wheel 10, which wheel is rigidly attached to the shaft 5. As here shown, the radial rods 6 which carry the semaphore 7 are mounted in a hub integral with the wheel 10. It will be seen that by pulling the connecting wire 9 to the right as viewed in Fig. 1, the semaphore 7 will be drawn away from the vertical position to which it is biased by gravity.

100 The other end of the wire 9 terminates in a chain 9^b which passes over and is attached to a grooved wheel 13 operated in a manner hereinafter described. Interposed in the connection between the wire 9 and the chain 9^b is a spring 9^c the function of which is to absorb shocks as hereinafter explained. The 110 chain 9^b is provided with trunnions 12 projecting from opposite sides thereof and

adapted to be engaged by a forked jaw 11 which is fixed to a shaft 11^a and is oscillated about this shaft as a center at times as will hereinafter appear. The wheel 13 and the 5 jaw 11 are actuated in the desired manner by means of an operating mechanism M which I will describe hereinafter.

The operation of the signal as thus far set forth is as follows: When the semaphore 10 7 is not acted upon by any force other than gravity, it hangs in the vertical position, which is the position in which it is shown in full lines in Fig. 1. If, while in this 15 position, the wheel 13 is turned in the direction indicated by the arrow thereon, the semaphore 7 will be swung in opposition to the force of gravity into a position such as that indicated in dash lines in Fig. 1. This is what I will term the "proceed" position, that is, the position in which the 20 signal indicates that no train is approaching and that therefore a traveler on the highway may proceed across the railway track in safety. If desired, a fixed shield 25 may be attached to the arm 3 to obscure the semaphore 7 while in the proceed position, such shield preferably being arranged to obscure both faces of the semaphore. As the wheel 13 turns to wind the chain 9^b 30 thereon, the trunnions 12 fit into recesses 13^a cut into the rims of the wheel, so that the chain is not raised out of the groove in this wheel. Assume now that when the 35 semaphore 7 is in the upper or "proceed" position, the wheel 13 is released and the forked jaw 11 is caused to oscillate. This jaw, acting on the trunnions 12, will exert 40 intermittent pulls to the right on wire 9 and so will cause the semaphore 7 to oscillate through a suitable angle on opposite sides of its vertical position; the limits of 45 this oscillation may be as indicated by the full and the dash lines in Fig. 3. This oscillation of the semaphore constitutes what I will term the "stop" or "danger" indication, that is, it conveys to a traveler on the highway the information that a train is 50 approaching and that it is therefore dangerous to cross the track. The period of oscillation of the jaw 11 is preferably the same as the natural period of oscillation of the semaphore 7.

Referring now to Figs. 4, 5, 6 and 7, I will explain the structure and operation of 55 the mechanism M by means of which the desired operations of the wheel 13 and jaw 11 are accomplished.

The mechanism comprises an inclosing casing and framework 14 in which is journaled a shaft 13^b to which the wheel 13 is rigidly attached. At the inner end of this 60 shaft, and rigidly attached thereto is a segmental gear 15 which meshes with a pinion 16 freely mounted on a shaft 17 65 which also is journaled in the framework 14.

This pinion 16 is operatively connected at times, through a directional clutch as will be hereinafter explained, with a gear 18 also mounted to rotate freely on the shaft 17. Meshing with the gear 18 is a pinion 19 70 which is integral with a gear 20 and both of which are mounted to rotate freely on the shaft 13^b. The gear 20 meshes with a pinion 21 which is rigidly attached to the shaft 17. 75

Operatively connected with the shaft 17 are an electric motor E and a holding device H, both of which are shown diagrammatically in Fig. 4 for the sake of simplicity. The motor E may be of any desired 80 type; as here shown it is a two phase induction motor comprising a rotor 23 attached to shaft 17 and two stator windings 24 and 24^a. The holding device H may be of any desired type, and as here shown it is similar 85 to the device disclosed in United States Letters Patent No. 1170360, granted to John D. Taylor on February 1, 1916; this device comprises a rotor member 25 operatively connected with the shaft 17, and an 90 energizing winding 26. It is understood however that any desired type of holding device may be employed, the essential thing being that when this device is energized it shall resist the torque exerted on the shaft 17 by the warning semaphore 7 when the latter occupies the position in which it is shown in dotted lines in Fig. 1, and that when the device is deenergized it shall permit free rotation of the shaft 17. 95

The angle of oscillation of the wheel 13 is limited by a stop device as shown in Fig. 7. This device comprises a member 28 fixed to shaft 13^b and provided with two wings 100 adapted to engage a shoulder 27^a formed on a block 27. This block is mounted to slide in suitable guides formed in the casing 14, and its downward movement is limited by a screw 29. The upward movement of this block is limited by another screw 30 between 110 which and the block is a shock-absorbing spring 31.

The forked jaw 11 is fixed to a shaft 11^a as hereinbefore stated, and this shaft is mounted to oscillate in suitable bearings in 115 the frame 14 as shown in Fig. 4. Fixed to this shaft at its inner end is a crank arm 32 (see Fig. 5) in which is journaled a roller 32^a which coacts with a cam 22 attached to the face of the gear 18 and shaped substantially as shown in Fig. 5. Rotation of this cam therefore causes oscillation of the 120 jaw 11 which in turn causes oscillation of the semaphore 7 as hereinbefore described.

It has already been pointed out that the 125 gear 18 and the pinion 16 are connected by means of a directional clutch. Referring to Figs. 4 and 6, this clutch as here shown is of the ball type, comprising a circular disk 33 integral with the pinion 16, which 130

disk is located in a cylindrical recess 34 in the face of gear 18. The surface of the disk 33 is provided with triangular notches 37 in which are located balls 35, and these 5 balls are pushed into wedging position by springs 36 in the usual and well known manner. It will be seen therefore that when the gear 18 is rotated in the direction of the arrow *a* in Fig. 6 the clutch is operative 10 to drive the pinion 16 and the wheel 13 is then turned in such direction as to raise the banner 7 to the dash line position in Fig. 1; but when the gear 18 is rotated in the opposite direction the clutch becomes inoperative 15 so that no torque is transmitted to the wheel 13.

Operatively connected with the shaft 13^b 20 is a circuit controller C comprising two rotatable contact segments 40 and 41 co-operating with fixed contact fingers as shown in Fig. 4. These contact segments are attached to a shaft 42 to which is fixed a gear 39, and this gear meshes with another gear 38 attached to the end of shaft 13^b.

25 In Fig. 4 I have shown a portion of a railway track R over which traffic moves in the direction of the arrow, and crossing this track at grade is a highway or street S. A portion of the track to the right of the 30 highway crossing is divided into an insulated track section by insulated joints 44, and the rails of this section form part of a track circuit which comprises also a battery 43 connected across the rails near one 35 end of the section and a track relay T connected across the rails near the other end of the section.

The motor E and holding device H are 40 operated by alternating current from a suitable source which as here shown is a transformer 46, and the supply of current to these devices is controlled by the track relay T and the circuit controller C. I have also shown a hand switch 47 for disconnecting 45 the transformer from the signal when desired.

The operation of the signal as a whole is as follows:

I will first assume that the track circuit is 50 unoccupied and that the hand switch 47 is open as shown in Fig. 4. The motor E and holding device H are then deenergized, so that the parts of the mechanism M are in the positions in which they are shown in 55 Figs. 4 and 5, and the semaphore 7 hangs vertically as shown in Fig. 1. If now the track section remains unoccupied and hand switch 47 is closed, the windings of motor E will become energized; the circuit for 60 winding 24^a is from secondary of transformer 46 through wire 48, contact segment 41, reactance 49, wire 50, winding 24^a, wire 51, wire 52 to transformer 46; the circuit for winding 24 is from secondary of transformer 46 through wire 48, segment 41, wire

53, upper point of relay contact 54, wire 55, winding 24, wire 56, upper point of relay contact 57 to transformer 46. The currents in the two windings of motor E are displaced in phase by the reactance 49, and the 70 phases in these two windings are in such relation as to cause the motor to drive the gear 18 (through the medium of gears 21, 20 and 19) in the direction indicated by the arrow *a* in Fig. 6. The clutch is then operative 75 to connect gear 18 and pinion 16, so that wheel 13 is turned in such direction as to draw the semaphore 7 to the right as viewed in Fig. 1. When the semaphore reaches substantially the dash line position 80 shown in Fig. 1, both motor winding circuits are opened by contact segment 41, and the circuit for the winding 26 of the holding device H is closed by segment 40. This latter circuit is from the secondary of transformer 46 through upper point of relay contact 58, wire 59, winding 26, wire 60, contact segment 40, and wire 52 to the transformer. The motor E therefore becomes de-energized, and the holding device H is energized 90 to retain the semaphore in the upper or "proceed" position. The mechanical stop 28 prevents overrunning this position. While the semaphore is being drawn to the "proceed" position the cam 22 is of course 95 rotating. This does not, however, cause oscillation of the jaw 11; the jaw will merely be moved to its extreme right hand position as viewed in Fig. 1 and will remain there, there being no force to cause it 100 to return as the cam recedes from its follower 32^a. Oscillation of the jaw during this movement of the semaphore would do no harm however, because soon after the semaphore leaves the vertical position the trunnions 105 12 move out of the path of the jaw 11.

I will now assume that the signal is in the proceed position and that a train enters the track circuit section, causing relay T to 110 open. The opening of the upper point of relay contact 58 opens the circuit for the holding device H so that the semaphore begins to fall by gravity, thus causing rotation of wheel 13 and the entire train of 115 gears in the direction opposite to that in which these parts moved while driving the signal to the proceed position. A very slight movement of the parts is sufficient to close contact 41, whereupon the motor E 120 again becomes energized. The circuit for the motor winding 24^a is the same as before, but the circuit for winding 24 is now from the lower transformer secondary terminal through wire 48, contact 41, wire 53, lower 125 point of relay contact 54, wire 56, winding 24, wire 55, wire 55^a, lower point of relay contact 57 to the upper terminal of the transformer secondary. The connection of winding 24 with the transformer secondary is 130

thus reversed, hence the direction of rotation of motor E is reversed. Gear 18 now rotates in the opposite direction and therefore does not drive pinion 16. As soon as 5 the semaphore falls to such point that the trunnions 12 engage the jaw 11 this jaw begins to exert periodic pulls on wire 9, and the semaphore is then caused to oscillate or "wag" through substantially the angle indicated in Fig. 3, thus giving the danger or "stop" indication. As soon as the entire 10 train has passed the highway S, relay T becomes energized and the direction of rotation of the motor is reversed, thus causing 15 the semaphore 7 to be again swung to and held in its "proceed" position.

Attached to the shaft 5 (Fig. 2) are two contact rings 61 (see also Fig. 4) to which the lamps 8 are electrically connected; and 20 bearing on these rings are two fixed brushes, one of which is connected directly to the upper transformer secondary terminal and the other of which is connected with the lower secondary terminal through the lower 25 point of relay contact 58. Hence as long as the track relay T is energized the lamps 8 are extinguished, but when a train approaches and causes deenergization of the relay so that the banner 7 is caused to oscillate, the lamps become illuminated. 30

It will be observed that in case of failure or breakage of any part of the mechanism between the wheel 10 and the holding device H, the semaphore 7 will fall to the vertical 35 position, thus indicating to a traveler on the highway that the signal is out of order and that he must rely entirely on his own senses to cross the railway in safety. The same result follows in case of failure of the source 40 of current supply for the signal.

Although I have herein shown and described only one form of signal embodying my invention, it is understood that various changes and modifications may be made 45 therein within the scope of the appended claims without departing from the spirit and scope of my invention.

Having thus described my invention, what I claim is:

50 1. A railway crossing signal comprising a pendulum - like warning member mounted to oscillate, electromagnetic means for causing said member to swing to and fro continuously, and electromagnetic means for holding said member in an inclined position.

2. A railway crossing signal comprising a pendulum-like warning member mounted to oscillate, electromagnetic means for causing said member to swing to and fro continuously to indicate danger, and electromagnetic 60 means for holding said member in an inclined position to indicate safety.

3. A railway crossing signal comprising a pendulum-like warning member mounted to oscillate, electromagnetic means adapted 65 when energized to cause said member to swing to and fro continuously, and other electromagnetic means adapted when energized to hold said member in an inclined position. 70

4. A signal comprising a warning member mounted to oscillate and biased to one indicating position, an electric motor, means operated by said motor during rotation in one direction for moving said member 75 against its biasing force to another indicating position, and means operated by said motor during rotation in the other direction for causing oscillation of said member.

5. A railway crossing signal comprising a 80 pendulum-like warning member mounted to oscillate, means for causing continuous swinging of said member, electromagnetic means for operating said first-mentioned means, and electromagnetic means for holding said member in an inclined position. 85

6. A railway crossing signal comprising a pendulum-like warning member mounted to oscillate, an electric motor having a member which rotates when the motor is energized, 90 means operated by said motor member for causing said warning member to swing to and fro continuously, and electromagnetic means for holding said warning member in an inclined position. 95

7. A signal comprising a warning member mounted to oscillate and biased to one indicating position, an actuating connector operatively connected with said member and adapted to swing the member away from its 100 biased position, means for exerting a steady force on said connector to move the member to and hold it in another indicating position in opposition to its bias, a trunnion fixed to said connector, a jaw mounted to oscillate in 105 operative relation to said trunnion, and electrical means for operating said first-mentioned means and for causing oscillation of said jaw.

8. A railway crossing signal comprising a 110 pendulum-like warning member biased to an intermediate position wherein it gives a warning indication, means for causing continuous oscillation of said member to give an indication of danger, and means for holding said member in an inclined position 115 wherein it gives a safety indication.

In testimony whereof I affix my signature in presence of two witnesses.

FRANK T. VANATTA.
